UNITED STATES PATENT OFFICE.

WILLIAM F. KNAP, OF DES MOINES, IOWA.

BOOK-COVER.

1,109,846.

Specification of Letters Patent.

Patented Sept. 3, 1914.

Application filed February 18, 1914. Serial No. 318,464.

To all whom it may concern:

Be it known that I, WILLIAM F. KNAP, a citizen of the United States, residing at Des Moines, in the county of Polk and State of Iowa, have invented certain new and useful Improvements in Book-Covers, of which the following is a specification.

My invention relates to improvements in book covers, and the main object of my invention is the provision of a flexible leather cover of ornamental and attractive appearance, which will provide a cover or protector for books of various kinds, and which can be instantly applied and removed from the covers of the book.

Another object of my invention is the provision of a flexible leather cover which will be constructed from a single strip or blank and which will have upon its engaging cover portions means for carrying a pencil and also a card case or pocket book, making the device highly useful as a book cover or for other purposes.

Another object of my invention is the provision of a cover of the character and for the purpose stated, constructed from a single blank and carrying upon its inside a card case or pocket-book and pencil receiver, and having upon its outer face an attached securing flap and carrying handle, the whole structure producing an efficient, useful and highly desirable article.

With these objects in view, the invention consists in the book cover made from a single strip or blank, and in the novel construction and arrangement of parts, substantially as shown, described and particularly defined by the claim.

Figure 1 represents a plan view of the cover, shown in open condition, looking at the outside and partly broken away to disclose details of construction. Fig. 2 represents a similar view looking at the inner side or face of the cover, and Fig. 3 represents a sectional view on line 3—3 of Fig. 2. Fig. 4 represents a plan view of the cover in closed and secured position, and Figs. 5 and 6 represent plan views of the inner and outer faces of a cover of slightly modified construction.

In manufacturing the book cover, I employ a lining sheet A, to which is secured by the turned edge B, the outer blank or cover portion C, which is made from a sin-

gle strip of leather or flexible material and has its ends turned in providing the flaps D, which provide the pair of end pockets E, in which the covers of the book are received and retained by the flaps D, said flaps as well as the lining being retained by the turned-in edge B, which is secured by the stitches E'.

From this construction it will be observed that the cover comprises the lining, the flexible outer covering and the end flaps which retain the covers of the book, and upon one of the flaps D is secured the case F, which provides a convenient card case or pocket book, and upon the other flap is secured the elongated small pocket G, which forms a pencil receiving receptacle, thus providing an outer book cover and placing upon the inside a card case or purse and a pencil pocket, thus disposing the cover and case and pocket in the most desirable and advantageous relation. The cover is further provided upon one side with a slit H in which is secured by stitches J the tab K carrying the socket plate L, which engages the stud fastening L' carried by the other side of the cover, this construction forming a most desirable means for fastening the cover upon the book and also protecting the card case or purse and the pencil holder.

Another important feature of my invention is the manner of securing the carrying handle M, which consists in placing between the lining and cover the base strips N and securing thereon the handle retaining strips O, which pass through slits P in the cover and engage the enlarged or flaring ends M' of the carrying handle and thus provide a convenient means for carrying the article and also a novel means for retaining the handle in the cover.

From the foregoing description, taken in connection with the drawings, the manner of using and the many advantages of my invention will be readily understood, and it will be apparent that the article can be used as a book cover, with its several attachments performing their desired functions, or it may be used solely as a card case or purse and pencil carrier, and that in any event it will prove thoroughly efficient and desirable. It will also be noted that the article will perform its manifold purposes in a practical manner, is highly ornamental and attractive, can

be made from any proper material, and is calculated to prove a most useful and desirable article.

I claim:

5 The herein described article, consisting of the inner lining, the outer cover portion having the pair of end flaps, and the securing edge for retaining the lining, cover and flaps, the strips mounted upon the lining between the lining and cover, the handle retaining strips fastened to said strips, the handle having the flaring ends and retained by the

10 handle-retaining strips, and the tab secured to one end of the cover and having a socket plate and a stud upon the other end of the cover to be engaged by said socket plate, for fastening the two sides of the cover.

15 In testimony whereof I affix my signature in presence of two witnesses.

WILLIAM F. KNAF.
